UNITED STATES PATENT OFFICE.

SAMUEL E. HARRISON, OF JERSEY CITY, NEW JERSEY.

IMPROVEMENT IN PAPER-FILES.

Specification forming part of Letters Patent No. 126,053, dated April 23, 1872.

To all whom it may concern:

Be it known that I, SAMUEL E. HARRISON, of Jersey City, in the State of New Jersey, have invented an Improvement in Paper-Files; and the following is declared to be a correct description thereof.

This invention relates to an improvement in means for holding newspapers, periodicals, letters, &c., in their proper relative position, and allowing additions to be made from time to time. I make use of a bar or slat of wood, or other material, rather longer than the back of the periodical to be connected thereto, and at the ends thereof are notches for a thread, that is passed along the fold through the paper near the middle of the back over a hook within the slat, and thence to the notch at the other end of the slat. An eye-pointed needle is employed to perforate the paper and convey the thread to the hook, and at the back of the slat is a movable case for holding the thread and the needle when not in use.

In the drawing, Figure 1 is a longitudinal section of the file complete and in use. Fig. 2 is a sectional plan at the line xx , and Fig. 3 is a view at the back of the slat.

The slat a has notches b b' at the ends, and an opening or mortise, c , near the middle, or if there is more than one mortise, c , they should be nearly equidistant from the ends. The hook d is in a recess at the back of the slat a . The thread is attached at one end at one of the notches or incisions b , there being an eye-

pointed needle, e , upon the thread or cord. By the use of the needle e the thread is carried through the folded sheet near the middle and hooked upon the hook d ; thence it passes along the fold of the sheet and is fastened in one of the incisions b' . Upon applying another number of the paper or periodical the before-named operations are repeated, and the cord or thread is then attached at b . The supply of thread is, for convenience, kept in the case f , wound upon the end-hooks i i , which case f also holds the eye-pointed needle e , and the case is kept in contact with the back of the slat a by elastic bands g g , one at each end.

By this manner of attaching papers or periodicals together and to a holding-file, they will be firmly held in place, but the sheets can be turned freely.

I claim as my invention—

1. The slat a , notched at the ends, and provided with the mortise c and hook d for receiving the thread or cord that holds the paper to the file, as and for the purposes set forth.
2. In combination with the foregoing, the case f for holding the thread and the eye-pointed needle, as specified.

Signed by me this 15th day of January, A.D. 1872.

SAMUEL E. HARRISON.
